(57) **CLAIM**

The ornamental design for an arm elevation pillow, as shown and described.

DESCRIPTION

FIG. 1 is a front right perspective view of an arm elevation pillow showing my new design;

FIG. 2 is an exploded view of FIG. 1;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a rear view thereof.

All broken lines in the drawings depict portions of the arm elevation pillow that form no part of the claimed design.

1 Claim, 8 Drawing Sheets
